CLAIM

The ornamental design for a combination hair brush and pick, as shown and described.

DESCRIPTION

FIG. 1 is a side elevational view of a combination hair brush and pick, showing my new design, the opposite side being a mirror image thereof;
FIG. 2 is a top plan view thereof;
FIG. 3 is a bottom plan view thereof;
FIG. 4 is an elevational view taken from the brush end;
FIG. 5 is an elevational view taken from the pick end.
